METAL AWNINGS

Herbert M. Helt and Philip Fellman, Pittsburgh, Pa., assignors to National Aluminum Products Company, Pittsburgh, Pa., a corporation of Pennsylvania

Application April 6, 1953, Serial No. 346,824

2 Claims. (Cl. 20—57.5)

This invention relates to new and useful improvements in a metal awning, such as an aluminum awning, but may also be applied to awnings made of other metals or other materials, such as plastic or wood.

Recently, metal awnings have come into wide-spread use. However, metal awnings of commonly known construction have certain disadvantages which have provided serious objections. For example, metal awnings of the type comprising top and bottom pans whose sides overlap are generally assembled and maintained in proper relationship by fastening means, such as screws, bolts or supporting strips. Such fastening means have the inherent disadvantage of necessitating drilling of holes through the top and bottom pans which tend to promote leakage therethrough of rain water. Also such fastening means are generally flimsy or of very limited mechanical strength, therefore providing weak points in the general construction or assembly which are likely to become ruptured or broken as the result of strong winds or storms. In fact, one of the most serious objections to metal awnings of conventional construction is that they are very apt to be blown apart by very strong winds, such as occur during winter, because of the above mentioned weaknesses, thus requiring frequent repairs or replacement.

A still further disadvantage of well known types of metal awnings is that their requirement for fastening means, such as screws, bolts or supporting strips, for holding the top and bottom pans together, not only provides weak and leaky points in the mechanical assembly, particularly as the result of loosening of the fastening means, but adds considerably to the cost of assembly or construction, since numerous fastening means or strips are required at spaced points, which is very time consuming for the workman.

An object of the present invention is to provide a novel metal awning which is devoid of the above named disadvantages of metal awnings of conventional construction, and which is devoid of screws, bolts, fastening strips, or similar fastening means throughout the entire top covering surface, therefore, which eliminates the possibility of leakage of rain water or melted snow through holes provided for such fastening means, and thus which assures complete protection against leakage of rain or snow.

A still further object of the present invention is to provide an improved metal awning comprising top and bottom pans which have interlocked flanges which provide an amazing increase in mechanical strength and rigidity of the awning, such as to practically eliminate the possibility of being blown apart by severe wind storms.

A still further object of the present invention is to provide a metal awning assembly, including top and bottom pans which are of such shape as to be simple in construction and inexpensively manufactured, also which can be easily and quickly assembled, therefore which greatly reduces manufacturing cost.

Other objects and advantages of our invention will be

come apparent from a study of the following description taken with the accompanying drawing wherein:

Figure 1 is a perspective view of a metal awning embodying the principles of our invention, and in which 5 a portion is cut away to more clearly illustrate the framework.

Figure 2 is an enlarged, transverse, cross-sectional view taken along line 2—2 of Figure 1.

Figure 3 is an enlarged fragmentary cross-sectional 10 view similar to Figure 2 but showing spaced apart the interlocking flanges of the top and bottom pans.

Figure 4 is a similar view of a modified form of the flange construction of the top pan, and

Figure 5 is an enlarged, transverse, cross-sectional view 15 taken on line 5—5 of Figure 1 and more clearly showing the wall flashing and cap flashing assembly.

Referring more particularly to Figure 1 of the drawing, it will be noted that the framework for the metal awning shown comprises side cross-strips or projections 1, of substantially L shaped cross-section, and metal rafters 2 of similar cross-section, extending angularly of the cross-strips. Metal louvres 3 are fastened to these cross-strips and rafters by means of rivets, screws, bolts, or other suitable fastening means 4. Louvres 3 form the side portions of the awning and are provided with flanged marginal portions 3a along the sides thereof, which extend angularly in a rearward direction, and which are spaced apart in parallel relationship to corresponding flanges of adjacent louvres, so as to provide vertical 25 spaces therebetween to allow the escape of air that would otherwise be trapped under the awning.

Also forming a part of the framework is a wall flashing 7, extending across the top ends of the rafters and adapted to be secured to and sealed to a wall by caulking 30 or sealing compound. The wall flashing is of substantially channel shape cross-section and has a horizontal top flange integrally extending at right angles to the vertical wall engaging flange thereof. To such top flange is fastened a cap flashing 8 by means of metal screws 9 or other suitable fastening means at the ends thereof. The cap flashing 8 extends angularly downwardly so as to provide a cover for preventing the entry of rain water directly into the gutter portion of the wall flashing, the latter provided with fastening means such as bolts and nuts for fastening the top ends of the bottom pans to the wall flashing. Thus any possibility of leakage of rain water through such fastening elements is prevented.

The framework is reinforced by cross-braces or strips 10, whose lower ends are fastened to the flanged end 50 portions of the side cross-strips 1, and whose upper ends are fastened to a central portion of wall flashing 7.

The top of the awning is formed by plurality of top pans or covers 11, and bottom pans 12, both of channel shape construction.

An important and outstanding feature of the present invention relates to the manner in which the bottom pans 12 are fastened to a metal runner or cross-piece 13, as well as to the manner the top and bottom pans are fastened together. More specifically, the runner or cross-piece 13 is of channel shape cross-section, and its uppermost flange is provided with pairs of upwardly and outwardly extending tabs or lugs 14, which are simply formed by a punching process and preferably provided with a bent out portion 14a centrally of the tab for providing greater rigidity and holding power of the tabs.

A very important feature of the present invention resides in the shaping of the flanges of the top and bottom pans so that such flanges will interlock snugly and their strength will be added to provide mutual reinforcement 70 so as to provide an amazing increase in rigidity of the top and bottom pan assembly.

Top pan 11, for example, is provided with side flanges,

each having an inwardly bent portion 11a and an adjoining downwardly and outwardly flanged central portion 11b and an inwardly bent end portion 11c. The bottom pan 12 has similar portions 12a, 12b, 12c respectively. It will be apparent from a study of Figures 2 and 3 that when the top and bottom pans are in assembled relationship the inwardly bent end portions of the bottom pan 12 will fit into the inwardly bent portions 11a of the top pan, whereas the inwardly bent end portions 11c of the top pan flange will fit into the inwardly bent portion 12a of the bottom pan. Thus the flanges of the top and bottom pans will become securely interlocked and prevent any possibility of relative vertical movement.

Figure 4 shows a modification of the invention wherein the bottom pans 12 are identical in construction to those shown in Figures 2 and 3 but wherein the top pans are provided with straight flanges 11d which terminate in inwardly bent end portions 11e which fit into the inwardly bent portion 12a of the bottom pan to provide interlocking engagement.

The top and bottom pans are assembled in the following manner. First a pair of spaced bottom pans are placed on the upper flange of runner 13, flanges 12a of the bottom pans being slipped underneath a pair of oppositely directed tabs or lugs 14. A top pan is then placed so as to straddle the bottom pans and so that its downwardly extending flanges will become interlocked with the upwardly extending flanges of the bottom pans. The tabs 14 are then bent downwardly so as to tightly engage the inwardly bent or flanged portions 12a of the bottom pans. Thereafter an adjoining pair of top and bottom pans is assembled in a similar manner, that is, the pans or covers are assembled in succession. And as they are assembled they are pulled tightly toward the unassembled side to firmly interlock the flanges thereof into snug and tight engagement.

Although only one runner 13 is shown, it will be apparent that additional runners may be employed having similar tabs 14 for engaging the flanged or bent portions of the bottom pans, particularly for awnings of large areas or span.

The lower end portions of the top and bottom pans which are bent so as to extend vertically downward are also in interlocking relationship. Thus the flanges of the top and bottom pans are securely interlocked throughout their entire lengths to provide continuous reinforcement and so as to add greatly to the mechanical strength of the awning.

While two forms of interlocked flanges have been described, other shapes of side flanges for the top and bottom pans may be provided, or other interlocking portions may be struck from said flanges, to provide the necessary interlocking of these flanges and to prevent their relative movement in a generally vertical direction.

While the awning has been described as being made of metal, such as aluminum, it should be noted that the awning or parts thereof, such as the top and bottom pans, may be of plastic material or wood or other suitable material, instead.

While the top and bottom pan and supporting structure is described in connection with an awning, it will be readily apparent that it is also useful in the case of metal umbrellas of the common design, wherein the various pans extend radially outwardly from a center, progressively increasing in width in an outward direction, or it may be applied to canopies and other similar sun, rain or snow protective or shielding structures.

Thus it will be seen that we have provided an efficient metal awning, or similar structure, wherein the top and bottom pans forming the covering surface of the awning are supported and held together without the necessity of screws, bolts, supporting strips, or other fastening means, therefore which eliminates the tendency of leakage through the holes otherwise necessary for such fastening means, and which eliminates the points of mechanical

weakness provided by such fastening means; furthermore, we have provided a novel flange construction, or design, for top and bottom pans of an awning which may be securely interlocked to provide an amazing increase in rigidity and strength of the awning assembly by virtue of the mutual reinforcement provided by the adjoining flanges throughout their entire length instead of at spaced intervals; furthermore we have provided a metal awning having parts of simple construction which are inexpensive to manufacture, and which may be very easily and quickly assembled, in a manner to provide an amazing increase in strength and great reduction in cost of manufacture as compared to metal awnings of conventional construction.

While we have illustrated and described several embodiments of our invention, it will be understood that these are by way of illustration only, and that various changes and modifications may be made within the contemplation of our invention and within the scope of the following claims.

We claim:

1. An awning comprising a top covering surface formed of alternate, overlapping, top and bottom, longitudinally extending, substantially channel shaped pans sloping in a downward direction, and arranged in spaced, 25 staggered relationship, the top pans having upper, horizontal, flat web portions and having downwardly and inwardly extending side flange portions, the bottom pans having lower, horizontal, flat web portions, sharply, inwardly bent side flange portions extending substantially horizontally from the margins of the web portions of said bottom pans and terminating in upwardly extending portions of S-shaped cross-section, a framework for said awning including a transversely extending cross-piece for directly supporting the flat web portions of said bottom pans, said cross-piece including integral upwardly struck tabs extending substantially horizontally and in engagement with the upper surfaces of said sharply, inwardly bent side flange portions for securing the bottom pans to said cross-piece, the inwardly extending portions of said top pans extending into the fold of said sharply, inwardly bent side flange portions to reinforce it and to yieldingly clip the top and bottom pans in interlocking engagement.

2. An awning comprising a top covering surface formed of alternate, overlapping, top and bottom, longitudinally extending, substantially channel shaped pans sloping in a downward direction and arranged in spaced, staggered relationship, the top pans having upper, horizontal, flat web portions and having downwardly extending flanges of S-shaped cross section, the bottom pans having lower, horizontal web portions and sharply, inwardly bent side flange portions extending from the margins of the web portions of said bottom pans and terminating in upwardly extending portions, also of S-shaped cross section, such as to snugly engage the side flanges of the bottom pans throughout their entire height and thereby form a continuous, double layered side flange construction, the top and bottom pans being of identical cross-section so as to be interchangeable, a framework for supporting said bottom pans, said framework including fastening means extending from the top surface thereof for securely engaging said sharply inwardly extending side flanges of the bottom pans, whereby said top and bottom pans are yieldingly clipped in interlocking, and strongly reinforcing engagement throughout the entirety of the surfaces of the side flanges of the top and bottom pans.
